(57) **CLAIM**

The ornamental design for a pill dispenser, as shown and described.

DESCRIPTION

FIG. 1 is a front elevational view of a pill dispenser showing my new design;

FIG. 2 is a back elevational view thereof;

FIG. 3 is a left-side elevational view thereof;

FIG. 4 is a right-side elevational view thereof;

FIG. 5 is a top elevational view thereof;

FIG. 6 is a bottom elevational view thereof; and,

FIG. 7 is an isometric view of the device.
